GAS BURNER IGNITER

Robert S. Taylor, Evansville, Ind., assignor to
Servel, Inc., New York, N. Y., a corporation of
Delaware

Application March 1, 1945, Serial No. 580,372

4 Claims. (Cl. 158—115)

1

My invention relates to gas ranges and more particularly to igniters for oven and broiler burners of gas ranges.

In gas ranges it is desirable that the different burners be ignited from a single igniter, such as a constantly-burning pilot or an electric igniter. This is accomplished by providing flash tubes which convey fuel gas from the different burners to the single pilot where the gas ignites and the flame flashes back through the flash tubes and ignites the gas at the different burners. In order for a flash tube to function successfully, it is necessary that a combustible mixture of fuel gas and air be contained throughout the length of the flash tube. The lighting of top burners is a fairly simple procedure because the pilot is located at substantially the same level as the top burners and since the flash tubes are substantially horizontal, the flow of gas from the top burners injects a combustible mixture of gas and air throughout the length of the flash tubes. The oven and broiler burners of modern gas ranges are, however, generally located well below the top burners and hence well below the constantly-burning pilot. Therefore, with gases with slow rate of flame propagation, narrow explosive limits and/or specific gravities near to or greater than air, the problem of lighting the oven and broiler burners from a top burner pilot is more complex.

It is, therefore, an object of my invention to provide a simple, reliable means for igniting all the burners of a gas range from a single constantly-burning pilot.

Other objects and advantages of my invention will be apparent from the following description taken in connection with the accompanying drawing, wherein like reference numerals are used to designate like parts throughout the different views, and wherein:

Fig. 1 is a side view, partly in vertical section, of a gas range illustrating one embodiment of my invention;

Fig. 2 is an enlarged side view, partly in vertical section, of a gas valve incorporating my invention;

Fig. 3 is a sectional view taken on line 3—3 of Fig. 2;

Fig. 4 is a sectional view taken on line 4—4 of Fig. 2;

Fig. 5 is a sectional view taken on line 5—5 of Fig. 2;

Fig. 6 is a view similar to Fig. 2, but showing the valve in a different position;

Fig. 7 is a sectional view taken on line 7—7 of Fig. 6;

2

Fig. 8 is a sectional view taken on line 8—8 of Fig. 6;

Fig. 9 is a sectional view taken on line 9—9 of Fig. 6;

Fig. 10 is a side view, partly in vertical section, schematically illustrating a second embodiment of my invention;

Fig. 11 is an enlarged vertical sectional view of the gas valve illustrated in Fig. 10; and

Fig. 12 is an enlarged sectional view of a nozzle for injecting gas into a flash tube.

Referring to Fig. 1 of the drawing, 20 indicates generally a gas range having a top burner compartment 22, a plurality of top burners 24, 15 only one of which is shown, an oven 26 provided with a burner 28 and a constantly-burning pilot 30. Top burners 24 and constantly-burning pilot 30 are supplied with fuel gas from a manifold 32 by suitable connections (not shown). Oven 20 burner 28 is supplied with fuel gas from manifold 32 by means of a conduit 34, a valve 36, a conduit 38, a safety cut-out valve 40, a conduit 42 and a mixing tube 44. Safety cut-out valve 40, which may be of any suitable type, is provided with a pilot 40a and a thermal element 40b which causes the valve to open or close depending upon whether or not pilot 40a is lighted. A flash tube 46, for lighting pilot 40a, has one end positioned directly above pilot 40a and its 25 opposite end positioned adjacent constantly-burning pilot 30. A conduit 48 having an inlet connected to valve 36 and three outlet branches 48a connected to flash tube 46 supplies fuel gas to the flash tube. Each of the outlets 48a is 30 provided with a nozzle or restrictor 48b (Fig. 12).

Valve 36 in the form illustrated includes a cylindrical valve body 50 having a rotatable plug 52 fitted therein. A cap 54 is secured to the valve body and serves as a sealing means and 35 a guide for a valve stem 56 secured to plug 52. An operating knob 58 is secured to valve stem 56 and is provided with suitable indices (not shown) for indicating different positions of the valve plug. A coil spring 60 surrounds valve stem 56 and holds plug 52 tightly against cap 54. As shown in Figs. 2 and 6, valve body 50 is provided with suitable ports to receive conduits 34, 38 and 48. Valve body 50 is also provided with ports to receive an inlet conduit 62 45 and an outlet conduit 64 connected to a gas receiver or reservoir 66. Valve plug 52 is provided with a plurality of transverse ports 68, 70a, 70b and 72, with ports 70, 70a and 70b in substantially the same plane and opening into port 68. With valve 36 in closed position, as shown 50

in Figs. 2-5 inclusive, gas is supplied to reservoir 66 through conduit 34, port 78a, port 78b and conduit 62. However, as shown in Fig. 5, port 72 is out of communication with conduits 64 and 48; therefore, gas is stored in reservoir 66. In practice, reservoir 66 is made in the form of an expansible-contractible container, such, for example, as a bellows.

When it is desired to light the oven burner, knob 58 is turned from the "off" to the "on" position; that is, valve 36 is turned from the position shown in Figs. 2-5 inclusive to the position shown in Figs. 6-9 inclusive. In the "on" position, port 72 (Fig. 9) is in communication with conduits 64 and 48, port 78 is in communication with conduit 34, port 78b is out of communication with conduit 62 (Fig. 8) and port 68 is in communication with conduit 38 (Fig. 7). Therefore, the supply of gas to reservoir 66 is cut off and, due to the expansible-contractible form of the reservoir, the gas that is contained therein under pressure flows through conduit 64, port 72, conduit 48 and branch conduits 48a into flash tube 46 at spaced points along the length thereof. Simultaneous with flow of gas to the flash tube, gas also flows through conduit 34, port 78, port 74, port 68 and conduit 38 to safety cut-out valve 40 and pilot 40a. The gas that has been conveyed to flash tube 46 by branch conduits 48a mixes with the air contained therein to fill the flash tube throughout its length with a combustible air gas mixture, which mixture is ignited by constantly-burning pilot 30 and the flame is flashed back through the tube and ignites pilot 40a. The flame of pilot 40a now heats thermal element 40b which causes safety cut-out valve 40 to snap to open position, whereby gas flows through conduit 42 and mixing tube 44 to oven burner 28 where it is ignited by pilot 40a. Pilot 40a is always in open communication with conduit 38; therefore, whenever valve 36 is turned on gas is supplied to pilot 40a. Gas is not supplied to the oven burner, however, unless pilot 40a is lighted. If, for some extraordinary reason, pilot 40a fails to light when the oven gas valve 36 is turned on, the valve is turned off, whereby reservoir 66 is again charged with gas, then valve 36 is turned on causing gas from the reservoir to again fill the flash tube 46. The restrictors 48b in branch conduits 48a cause the gas to be conveyed uniformly through the several branches and also prevent flash-backs through the branches and into conduit 48.

In Figs. 10 and 11 of the drawing there is illustrated a second embodiment of my invention which is adapted to be incorporated in a gas range generally similar to that illustrated in Fig. 1. The construction and arrangement of the constantly-burning pilot, the flash tube, the safety cut-out valve, the pilot for the safety cut-out valve and the oven burner in the second embodiment are substantially identical with that illustrated in Fig. 1; therefore, a description of valve 36' is all that is necessary.

Valve 36' includes a body member 74 provided with transverse ports 76, 78 and 80 having conduits 34, 38 and 48, respectively, connected thereto. Ports 76 and 78 are in line and open into a cylindrical bore 82 formed in the valve body. Bore 82 is fitted with a cylindrical plug 84 provided with a transverse port 86, an axial port 88 in open communication with port 86, a transverse port 90 in open communication with port 88 and an annular recess 92 in open com-

munication with port 88. As shown, recess 92 is in open communication with a transverse port 80a formed in body member 74 in line with port 80. A closure or retaining nut 94 is threaded into the open end of bore 82 to seal the end of the bore and also serve as a guide for a cylindrical valve stem 96 attached to valve plug 84. Valve stem 96 is provided with an operating knob 98 and with a compression spring 100 positioned between the knob and the closure nut 94. A transverse pin 102 rigidly secures knob 98 on valve stem 96. As shown, valve body 74 is provided with a second cylinder bore 104 arranged in parallel relation with bore 82 and in open communication with ports 80 and 80a. A valve plug 106 is fitted in bore 104 and is provided with an annular recess 108 adapted to register with ports 80 and 80a. A retaining nut 110 is threaded into the open end of bore 104 to seal the end of the bore and to serve as a guide for a valve stem 112 attached to valve plug 106. Valve stem 112 is provided with a hemispherical head 114 and with a compression spring 116 which serves to yieldably hold the valve plug 106 in the position shown in Fig. 11.

In operation, knob 98 is rotated to bring the valve to open position, as shown in Fig. 11. This causes fuel gas to flow through conduit 34, port 76, port 86, port 78 and conduit 38 to safety cut-out valve 40 and pilot 40a. Simultaneous with the rotation of knob 98, or if desired after the knob has been rotated to register port 86 with ports 76 and 78, the knob is pushed inward or to the right, as viewed in Fig. 11, carrying valve plugs 84 and 106 with it and positioning recess 108 in line with ports 80a and 80. This causes fuel gas to flow through port 88, port 90, recess 92, port 80a, recess 108, port 80, conduit 48 and branch conduits 48a into flash tube 46. As before, the gas mixes with air contained in the flash tube filling the tube throughout its length with a combustible gas-air mixture; the mixture is ignited by constantly-burning pilot 30; the flame flashes through the tube to ignite pilot 40a; and the flame from pilot 40a heats thermal element 40b causing safety cut-out valve 40 to open the supply of gas to oven burner 28. After pilot 40a has been ignited, knob 98 is released, whereby spring 100 returns valve plug 84 to the position shown in Fig. 11 and spring 116 returns valve plug 106 to its "off" position.

Safety cut-out valve 40 and pilot 40a may be eliminated from each of the illustrated embodiments, in which case the lower end of the flash tube is located above or adjacent one of the ports of oven burner 28.

While I have illustrated and described but two specific embodiments of my invention, it obviously may take other forms and be variously applied within the scope of the following claims.

What is claimed is:

1. In a gas range, a top burner, a normally-lighted pilot adapted to light said top burner, an oven burner positioned appreciably below said normally-lighted pilot, a safety cut-out valve for controlling the supply of gas to said oven burner, an oven pilot, a generally vertical flash tube disposed with its lower end above said oven pilot and its upper end adjacent said normally-lighted pilot, means for supplying gas to said oven pilot and to said flash tube at a plurality of spaced points intermediate the ends thereof, whereby said flash tube is charged with a combustible air-gas mixture throughout its length which mixture

is ignited by said normally-lighted pilot and the flame flashes through said flash tube and ignites said oven pilot.

2. In a gas range, a top burner, a normally-lighted pilot adapted to light said top burner, an oven burner positioned appreciably below said normally-lighted pilot, a safety cut-out valve for controlling the supply of gas to said oven burner, an oven pilot, a vertical flash tube disposed with its lower end above said oven pilot and its upper end adjacent said normally-lighted pilot, and a valve for simultaneously supplying gas to said oven pilot and to said flash tube at points near each end and at a point intermediate the ends thereof, whereby said flash tube is charged with a combustible air-gas mixture throughout its length which mixture is ignited by said normally-lighted pilot and the flame flashes through said flash tube and ignites said oven pilot.

3. In a gas range, a normally-lighted pilot located at an upper elevation, a main burner located at a lower elevation, an upwardly-projecting flash tube disposed with its lower end adjacent said main burner and its upper end adjacent said normally-lighted pilot, a gas reservoir, a gas supply conduit, a multi-ported valve in said conduit, a conduit for conducting gas from said valve to a plurality of spaced points along the length of said flash tube, a conduit for conducting gas from said valve to said main burner, inlet and outlet conduits connecting said gas reservoir to said valve, the construction and arrangement of said valve being such that in one position of said valve said main burner is out of communication with the gas supply conduit, the inlet conduit of said reservoir is in open communication with the gas supply conduit and the outlet conduit of the gas reservoir is closed, and in another position of said valve said main burner is in open communication with said gas supply conduit, the inlet conduit of said reservoir is out of communication with the gas supply conduit and the outlet conduit of said reservoir is in open communication with the conduit which conducts gas to said flash tube.

4. In a gas range, a normally-lighted burner located at an upper elevation, a main burner located at a lower elevation, an upwardly-projecting flash tube disposed with its lower end adjacent said main burner and its upper end adjacent said normally-lighted burner, an expansible-contractible gas reservoir, a gas supply conduit, a multi-ported valve in said conduit, a conduit for conducting gas from said valve to a plurality of spaced points along the length of said flash tube, a conduit for conducting gas from said valve to said main burner, inlet and outlet conduits connecting said gas reservoir to said valve, the construction and arrangement of said valve being such that in one position of said valve said main burner is out of communication with the gas supply conduit, the inlet conduit of said reservoir is in open communication with the gas supply conduit and the outlet conduit of the gas reservoir is closed, and in another position of said valve said main burner is in open communication with said gas supply conduit, the inlet conduit of said reservoir is out of communication with the gas supply conduit and the outlet conduit of said reservoir is in open communication with the conduit which conducts gas to said flash tube.
